UNITED STATES PATENT OFFICE

PAUL W. DAVIS AND JAMES M. BOOTH, OF KANSAS CITY, MISSOURI

TRUSS

Application filed June 26, 1931. Serial No. 547,119.

This invention relates to trusses, and particularly to a device of the character having advantages over those of the prior art, novel means being provided for retaining pads in place without the employment of supports which press on the abdomen or which necessitate the use of shoulder straps or suspenders. Pressure on the abdomen is apt to cause an enlargement of the rupture by reason of the fact that the intestines are caused to exert pressure at the rupture and this invention, as stated, obviates such pressure.

It is a further object of this invention to provide pads which distribute pressure on the surfaces around the rupture and which relieve the localization of pressure at the rupture, as such localized pressure also has a tendency to exaggerate the rupture.

It is furthermore an object of the invention to provide novel bracing means for the pads which are so applied and fastened to the pads as to escape contact with the person wearing the truss, the said bracing element being yieldable in order that the movement of the body will not cause a distortion or movement of one pad under the influence of the movement of the other pad.

It is a further object of the invention to produce a truss of the character indicated which can be readily applied or removed, and wherein the devices for holding the truss in place are adjustable in order that they may be fitted to wearers of different sizes and proportions.

With the foregoing and other objects in view, the invention consists in the details of construction, and in the arrangement and combination of parts to be hereinafter more fully set forth and claimed.

In describing the invention in detail, reference will be had to the accompanying drawing forming part of this application, wherein like characters denote corresponding parts in the several views, and in which—

Figure 1 illustrates a view in front elevation of the truss applied;

Figure 2 illustrates a rear elevation thereof; and

Figure 3 illustrates a sectional view of the pads on the line 3—3 of Fig. 1, omitting

connections by which the truss is held on the wearer.

In this drawing 5, 5 denote pads and they are preferably elongated to such an extent that they will occupy spaces on the wearer reaching approximately from the pelvis bone to the hip bone and thereby providing support and strength to weakened muscles above the rupture.

Preferably the pads are formed by employing a filling of crushed cork or the like, covered with heavy canvas and faced with soft leather and then anchored to a metal plate, although the inventors do not wish to be limited with respect to the material employed in the formation of the pads. A two-part brace consisting of the plates 6 and 7 oscillates on pivots 8 and 9, respectively, and each of the pivots is carried by one of the aforesaid plates, which is identified by the numeral 10. It is shown in Fig. 3 that the brace is remote from the surfaces of the pads which are intended to contact the body of the wearer and the degree of this separation is such as to preclude contact of the brace and the body of the wearer. The plates 6 and 7 are so articulated or connected together by a member 11 as to permit one of the pads to move without liability of imparting undue movement to the other pad. The plates are furthermore provided with apertures such as 11^a to receive the connection 11 and the brace may be lengthened or shortened by applying the connection 11 in coinciding apertures of the plates when the said plates have been properly positioned.

As a means for securing the truss in place, each pad at its upper end may be provided with a fastening element 12 such as a ring which is engaged by a hook 13 on one end of a strap 14 which extends across the back approximately horizontally, the ends of the said strap embracing the side of the body and extending downwardly slightly, when in place, so that when it is anchored to the upper end of a pad, it tends to support the pad and, in conjunction with other devices, to be presently explained, holds the said pad in operative position. The pads are preferably positioned with their upper ends diverging.

A strap 15 is intended to extend horizontally across the body below the strap 14 and it is preferably provided with adjustable extensions such as 16 at its ends and the said extensions are provided with fastenings such as snap hooks which engage a ring such as 18 anchored to the pad.

The straps 14 and 15 are preferably two-part structures, the said parts being adjustably connected by buckles such as 19, but other appropriate devices for accomplishing this result may be used. Vertically disposed straps 20 and 21 connect the straps 14 and 15 and serve as supports for the lowermost strap 15 to prevent sagging of the same. Straps 22 and 23, preferably two-piece structures, each extend from one of the pads through the crotch of the wearer and have anchorages on the strap 15 preferably through the employment of short connections such as 24, each of which has one end looped around the strap 15 and secured thereto by stitching or the like, the said extension 24 being adjustably secured to the main portion 22 or 23 by adjustable devices 25 such as buckles. In referring to the connecting devices or fastenings, the inventors have described and illustrated one operative form, but it is understood that these may be modified to suit particular requirements without departing from the scope of the invention set forth in the claim.

It has been found that a truss made in accordance with the foregoing may be worn without discomfiture, without liability of exertion of pressure across the abdomen or bladder, and that the connection and leverage provided by the cooperating plates 6 and 7 allows an automatic adjustment of the pads during the movement of the body while bending to one side or the other, or while bending forwardly, and the provision of holding the pads in place without the employment of shoulder supporting elements is an added source of comfort for the user.

65 Should the wearer have a single rupture, the use of the two pads would be an advantage, as serving to strengthen the muscles on the other side and to guard against the development of a rupture, and it will furthermore serve to retain the pad on the ruptured side in effective operative position.

We claim:

55 In a truss, elongated pads, means for holding the pads in diagonal positions with their upper ends diverging, a two-part brace each part being pivotally connected to one of the pads and pivots by which the two parts of the brace are pivotally connected, a supporting strap adapted to extend horizontally on a plane above the upper ends of the pads with their ends adapted to embrace the sides of the wearer, fastenings by which the ends of the strap are connected to the pads, a strap adapted to occupy a position parallel with the first-
55 mentioned strap and therebelow, connections

by which the ends of the second mentioned strap are connected to the pads near their lower ends, and straps connected to the second mentioned strap at the rear and adapted to extend through the crotch of a wearer, the front ends of said straps having means by which they are connected to the pads near their lower ends.
